UNITED STATES PATENT OFFICE.

LARS YNGSTRÖM, OF FALU GRUFVA, FALUN, SWEDEN, ASSIGNOR TO STORA KOPPARBERGS BERGSLAGS AKTIEBOLAG, OF FALUN, SWEDEN, A CORPORATION.

ELECTRIC FURNACE.

1,001,915.

Specification of Letters Patent. Patented Aug. 29, 1911.

Application filed March 15, 1910. Serial No. 549,509.

To all whom it may concern:

Be it known that I, LARS YNGSTRÖM, a subject of the King of Sweden, and resident of Falu Grufva, Falun, in the Kingdom of Sweden, have invented certain new and useful Improvements in Electric Furnaces, of which the following is a specification, reference being had therein to the accompanying drawing.

10 As proved by experience the vault of crucible-shaped furnaces for the reduction of metals from ore by the aid of electric current is forcibly acted upon by the heat generated by the current and consequently is rapidly destroyed. The said disadvantage is removed in furnaces arranged and charged in accordance with this invention, which furnaces consist of a crucible or the like, forming the working or melting chamber, 15 and a stack-shaped chamber for feeding the material to the working chamber and located above the working chamber in such manner that there is a ring-shaped space between the walls of the stack-shaped chamber and the crucible, which space is filled 20 with material, forming a substitution for the said vault. One or more electrodes are inserted in the furnace through the said space and consequently surrounded by material.

In the accompanying drawing Figure 1 shows schematically and in a vertical section an electric furnace arranged in accordance with this invention. Fig. 2 shows in a vertical section a modified form of the furnace. Fig. 3 shows in the same manner another form of execution.

Ore, carbon, fusing material, etc., are charged into the stack-shaped chamber 2, 40 Fig. 1, located above the crucible-shaped furnace 1. The electric current, which may have any suitable number of phases, is supplied through the electrodes 3, one phase through each of the electrodes. The said 45 electrodes are inserted through the material located in the ring-shaped space 4 between the walls of the chamber 2 and the crucible 1. Between the said electrodes a heat focus 5 is generated by the current. The furnace 50 is charged not only through the chamber 2

but also through the ring-shaped space 4, so that the ordinary heat insulating vault above the said part of the furnace is substituted by material, the said material being renewed to the same extent as it is melted. 55 The produced metal and the slag are discharged at the bottom of the furnace through the tap-hole 6.

The furnace shown schematically in Fig. 2 differs from the furnace shown in Fig. 1 by one of the phases of the electric current being led into the furnace through a bottom electrode 7, which consequently is protected against combustion by the layer of molten metal, located on the same. 60

In Fig. 3 means are shown for controlling the quantity of air passing into the furnace through the space 4. For the said purpose the space 4 is shut off from the atmospheric air by a cover 9 preferably of sheet-metal 70 and located between the walls of the chamber 2 and the crucible and provided with charging openings 8 with closing means. The said openings 8 may simultaneously be adapted as air-holes. Instead of the said 75 arrangement the charging-opening of the chamber 2 may be provided with a bell 10 or be closed in any other suitable manner and an outlet pipe 11 for the gas connected with the top part of the chamber, which pipe is 80 provided with a damper 12. In the case last mentioned a further controlling of the quantity of air passing through the furnace can be effected by connecting a fan 13 with the pipe 11. The cover 9, provided with charging 85 openings may evidently be used in combination with the controlling means last described.

Having now described my invention, what I claim as new and desire to secure by Letters Patent is:

In an electric furnace, the combination of a crucible-like working chamber and a stack-shaped charging chamber located above the said chamber and projecting into proximity to the mouth of said working chamber leaving a space between the walls of the two chambers at the mouth of the working chamber and electrodes projecting into the working chamber in the said space between 100

the walls of the two chambers, the said electrodes being held in position by the material to be treated, whereby the said material to be treated may form a substitute for a cover and the heat insulating brick-work commonly employed between the walls of the two chambers.

In witness whereof, I have hereunto signed my name in the presence of two subscribing witnesses.

LARS YNGSTRÖM.

Witnesses:

ERNIE BRANDBERG,
H. W. RYDBERG.
